(57) **CLAIM**

The ornamental design for a multi-purpose medical imaging device support apparatus, as shown and described.

DESCRIPTION

FIG. 1 is a perspective view of the multi-purpose medical imaging device support apparatus;

FIG. 2 is a front elevation view thereof;

FIG. 3 is a rear elevation view thereof;

FIG. 4 is a top plan view thereof;

FIG. 5 is a bottom view thereof;

FIG. 6 is a right side elevation view thereof; and,

FIG. 7 is a left side elevation view thereof.

The broken line showing of a medical device, a light source, and a tongue depressor is for the purpose of illustrating portions of the article and forms no part of the claimed design.
